UNITED STATES PATENT OFFICE.

FRITZ KOBER, OF SUHL, GERMANY.

PLIERS FOR BENDING METAL PIPE.

No. 831,356.

Specification of Letters Patent.

Patented Sept. 18, 1906.

Application filed April 9, 1906. Serial No. 310,634.

To all whom it may concern:

Be it known that I, FRITZ KOBER, manufacturer, a subject of the German Emperor, residing at Suhl, Thüringen, in the German Empire, have invented certain new and useful Improvements in Pliers for Bending Metal Pipes, of which the following is a specification.

The present invention has for its object pliers for bending insulating-pipes which differs from pliers of the known kind in which at the bend the material in excess is forced into the inner side of the pipe by means of a blade fixed on one of the arms of the pliers, owing to the fact that in place of this single blade two or more of half the size are arranged opposite but laterally displaced relatively to each other in such a manner as to be positively displaceable. Owing to the division of the blade into two parts and their lateral displacement relatively to each other, the danger of fracture of the pipe where it is pressed in is largely reduced as compared with the constructions hitherto employed, as the indentation formed by one blade amounts to only about one-fourth of the periphery of the pipe, while with the known construction it extends over about one-half the periphery of the pipe. Accordingly a pipe bent by means of the tool in accordance with this invention will be far stronger than a pipe bent with the known form of tool. The blade-jaws are formed and fixed in such a way that any lateral give of the pipe to be bent is obviated. Further, a set-screw is provided on the pliers which screw prevents the pliers from being pressed together beyond the amount appropriate for the size of pipe which is being acted upon. This positive adjustment of the blades and minimum width of jaw present the further advantage that the tool may be utilized for any thickness of pipe and for any desired curvature, for by opening the blade-jaws wider than corresponds to the pipe to be bent a smaller bending of the pipe is obtained than when the jaws are exactly adjusted to the diameter of the pipe, while owing to the adjustability of the width of jaw the blades are prevented from cutting too deeply into the pipe. The other half of the pliers is provided with projections which serve as supports for the pipe to be bent and which, if desired, may be positively displaceable.

In the accompanying drawings, Figure 1 represents the pliers in front elevation. Fig. 2 is a section of the same through the blade-adjusting device. Fig. 3 shows the pliers in side elevation. Fig. 4 represents an insulating-pipe with indentations formed by the tool.

The pliers consists of the two two-armed levers *a* and *b*. Into the upper end of *a* a casing *c*, open in front, is let, its upper wall *d* being fixed only after the blade-jaws *e* have been arranged in position. The upper and lower walls of this casing serve for holding the set-screw *f* for the blade-jaws, while the casing itself serves to guide the blade-jaws. These jaws are provided at their rear part, which serves for their guidance, with right and left handed screw-threads, respectively, in which the set-screw furnished with corresponding threads engage so that by rotating the screw the jaws are caused to approach or recede from each other. In its front portion, but not at the middle of the same, each of the jaws *e* presents one or more recesses into which blades are fitted, these blades presenting a cutting edge which approximately corresponds to the diameter of the pipe, being so shaped that it is impossible for the pipe to be bent to give laterally. The blades are inserted in the opposite jaws with a relative lateral displacement, so that a recess *g* must be provided in each jaw for each blade facing the said jaw, this recess serving for the reception of the projecting part of the opposite blade when the jaws are screwed together. The upper end of *b* is provided with two projections *h*, lying symmetrically to the middle of the pliers and, if desired, positively displaceable, these projections being bent so as to approximately correspond to the diameter of the insulating-pipe to be bent for the purpose of more securely holding this pipe. The jaw may be adjusted for a minimum width by the set-screw *i*, carried through one of the levers of the pliers.

What I claim, and desire to secure by Letters Patent of the United States, is—

1. In a device of the character described, a casing carried by one member of the pliers, blades mounted in said casing and adapted to be laterally displaced relatively to each other, and means for adjusting said blades.

2. In a device of the character described, a casing carried by one member of the pliers,

blades mounted in said casing and adapted to be laterally displaced relatively to each other, means for adjusting said blades, and projections carried by the other member co-
5 acting with said blades.

3. In a device of the character described, a casing carried by one member of the pliers, jaws mounted in said casing, means for adjusting said jaws, blades having curved faces
10 carried by said jaws, and projections on the other member of the pliers.

4. In a device of the character described, a casing carried by one member of the pliers,

blades mounted in said casing and adapted to be laterally displaced relatively to each other, means for adjusting said blades, and means whereby the pliers may be set for a minimum width.

In testimony whereof I have hereunto set my hand, in presence of two subscribing witnesses, this 21st day of March, 1906.

FRITZ KOBER.
